UNITED STATES PATENT OFFICE

WILLY SKAWRAN, OF BERLIN-NIEDERSCHONHAUSEN, AND OTTO STEINER AND WILLY LOHS, OF BERLIN-CHARLOTTENBURG, GERMANY, ASSIGNEES TO SIEMENS & HALSKE, AKTIENGESELLSCHAFT, OF SIEMENSSTADT, NEAR BERLIN, GERMANY, A CORPORATION OF GERMANY

TELEGRAPHIC TRANSMISSION OF PICTURES

Application filed May 29, 1928, Serial No. 281,421, and in Germany June 2, 1927.

Our invention relates to improvements in the telegraphic transmission of pictures. Picture drum arrangements for picture telegraphy, wherein the picture drum is provided with a hood enveloping it, into which the drum is inserted in the dark room, so that it can be inserted in daylight into the receiving apparatus, are already known. The present invention concerns a special design and construction of this casket or hood, that can easily be manipulated and above all ensures a safe protection against inadvertent exposures of the light sensitive film.

The drawing shows an embodiment of the invention as an example:

Figure 1 shows an embodiment of the invention in longitudinal section,

Figure 2 is a top view thereof,

Figure 3 is a detail of the embodiment, viz.—the drum carrying shaft, and

Fig. 4 shows another detail of Fig. 1 on an enlarged scale.

The stem of the shaft *a* terminates in a cone *b* which carries the picture drum. The cone is hollow and is cut off or truncated at an angle and at the lowest place of the plane of truncation is provided with a slot *d*. The cone of the drum *e*, carries on its inside a pin *f* that slides, when the drum is pushed onto it along the inclined surface of truncation *c* thereby turning the cone, and finally drops into the slot *d*. By this means the abutment or register of the picture comes always into the same angular position in relation to shaft *a*, and if the shaft *a* is always coupled by means of a friction coupling registering at the correct phase, in the same angular position, to the synchronous motor. There is then no need of being concerned about the angular position when exchanging the drums, as long as the synchronism of the driving motor is maintained.

The casket or hood consists mainly of a cylindrical part *g* that is inserted into a guiding cylinder *h* fixed rigidly in the receiving apparatus itself. By means of a spring and groove the identical angular position in relation to one another is assured always.

The casket or hood remains in the apparatus during exposure. For the purpose of

exposing the drum to the light the cylinder of the hood and the guide cylinder are provided at some place with an excision or slot *i*. This slot is closed as against light by a shutter *k*, as long as the casket is not inserted into the exploring apparatus. The shutter *k* is shaped as part of a cylindrical surface and is fixed to the cover *l* of the hood cylinder, with which it can be displaced in relation to cylinder *g*. The lower seal of the casket or hood is formed by the drum itself, its edge *m* forming a light impervious seal against the edge *n* of the casket. To obtain this result the thread *p* is screwed into the drum by means of the knob *o*. By drawing up the knob *o* the drum is lifted off the cone *b* and is drawn out of the apparatus with the casket. A spring *q* is provided to prevent opening of the seal at *m* while doing so. In the dark room the drum can be extracted from the casket by unscrewing the screw *p*.

In the same manner the drum is, after insertion into the exploring apparatus, detached from the casket and pushed onto the cone *b* of the driving shaft, by a simple turning of the knob *o*.

The following safety devices, serve the purpose of preventing an inadvertent exposure of the light sensitive film or paper clamped on the drum. When the casket or hood is removed from the housing *h*, a pin *r* vertically movable in the cover *l* of the casket or hood (see Fig. 4) and depressed by means of a spring, engages into a hole *t* provided at the edge *u* of the hood *g* and thus makes a rotary movement of the cover *l* with respect to the hood and thereby the opening of the shutter *k* impossible. A pin *v* in the apparatus housing *h* itself releases this locking device when the casket or hood is inserted in the housing, by pushing pin *r* out of the hole *t*.

When the hood shutter *k* is opened, the nose *w* is caused to lie under the projecting edge *x*, that is firmly fixed to the housing of the apparatus. It is thus impossible to extract the casket or hood as long as the shutter is open. It would however still be possible to draw the casket or hood out after closing the shutter, without the drum being fixed.

in the casket or hood. This possibility is prevented by means of lever *y*. By means of the spring *z* the extremity of this lever is pressed into a hole *j* at the edge of the casket or hood and the rotation of the cover *l* is blocked so long till the knob *o* by screwing the thread *p* into the drum, actuates the lever *y*, and releases the connection between the cover and edge of the casket or hood.

10 The invention may, besides its application to picture rolls used in picture transmission, also be applied to oscillographs.

15 Various modifications and changes may be made without departing from the spirit and the scope of the invention, and we desire, therefore, that only such limitations shall be placed thereon as are imposed by the prior art.

We claim as our invention:

20 1. In apparatus for the telegraphic transmission of pictures, a picture drum, a hood impervious to light provided with an aperture and adapted to envelope said drum, a shutter for closing said aperture, a light impervious housing adapted to house said hood, and means for permitting the removal of said hood together with said drum from said housing only when said aperture in said hood is closed by said shutter.

30 2. In apparatus for the telegraphic transmission of pictures, a picture drum, a hood impervious to light provided with an aperture and adapted to envelope said drum, a shutter for closing said aperture, a light impervious housing adapted to house said hood, and means for permitting the removal of said hood together with said drum from said housing only when said aperture in said hood is closed by said shutter, said hood remaining immovable after insertion into said housing, while said drum is adapted to be fixed on its spindle in a correct phase relation.

45 3. In apparatus for the telegraphic transmission of pictures, a picture drum, a hood impervious to light provided with an aperture and adapted to envelope said drum, a shutter for closing said aperture, a light impervious housing adapted to house said hood and including a guiding cylinder, means for permitting the removal of said hood together with said drum from said housing only when said aperture in said hood is closed by said shutter.

55 4. In apparatus for the telegraphic transmission of pictures, a picture drum, a hood impervious to light provided with an aperture and adapted to envelope said drum, a shutter for closing said aperture, a light impervious housing adapted to house said hood and including a guiding cylinder, said guiding cylinder having a slot in registry with the aperture in said hood, said slot and aperture extending parallel to the common axis of said hood and cylinder, and means for permitting the removal of said hood together with said drum from said housing only when

said aperture in said hood is closed by said shutter.

5. In apparatus for the telegraphic transmission of pictures, a picture drum, a hood impervious to light adapted to envelope said drum, a light impervious housing adapted to house said hood and including a guiding cylinder, both said guiding cylinder and said hood having at the identical place a slot parallel to the common axis, a shutter shaped corresponding to the peripheral surface of said hood and adapted to control said slot, and means for permitting the removal of said hood together with said drum from said housing only when the slot in said hood is closed by said shutter.

6. In apparatus for the telegraphic transmission of pictures, a picture drum, a hood impervious to light adapted to envelope said drum, a light impervious housing adapted to house said hood and including a guiding cylinder, both said guiding cylinder and said hood having at the identical place a slot parallel to the common axis, a shutter shaped corresponding to the peripheral surface of said hood and adapted to control said slot, a cover for said hood rotatable with respect thereto, means for rigidly connecting said shutter with said cover, and means for permitting the removal of said hood together with said drum from said housing only when the slot in said hood is closed by said shutter.

7. In apparatus for the telegraphic transmission of pictures, a picture drum, a hood impervious to light adapted to envelope said drum, a light impervious housing adapted to house said hood and including a guiding cylinder, both said guiding cylinder and said hood having at the identical place a slot parallel to the common axis, a shutter shaped corresponding to the peripheral surface of said hood and adapted to control said slot, a cover for said hood rotatable with respect thereto, means for rigidly connecting said shutter with said cover, a projection upon said shutter outside said hood, a projecting portion on said housing, said projections cooperating in such a manner, that the removal of said hood and said drum is prevented whilst said shutter is open.

8. In apparatus for the telegraphic transmission of pictures, a picture drum, a hood impervious to light adapted to envelope said drum, a light impervious housing adapted to house said hood and including a guiding cylinder, both said guiding cylinder and said hood having at the identical place a slot parallel to the common axis, a shutter shaped corresponding to the peripheral surface of said hood and adapted to control said slot, a cover for said hood rotatable with respect thereto, means for rigidly connecting said shutter with said cover, said hood having an aperture on the side at which said shutter is located, and a spring-controlled pin fas-

tened on said cover adapted to engage said aperture when said shutter is in the closed position and said hood is taken out of said housing.

5 9. In apparatus for the telegraphic transmission of pictures, a picture drum, a hood impervious to light adapted to envelope said drum, a light impervious housing adapted to house said hood and including a guiding cylinder, both said guiding cylinder and said hood having at the identical place a slot parallel to the common axis, a shutter shaped corresponding to the peripheral surface of said hood and adapted to control said slot,
10 15 a cover for said hood rotatable with respect thereto, means for rigidly connecting said shutter with said cover, said hood having an aperture on the side at which said shutter is located, a spring-controlled pin on said cover
20 adapted to engage said aperture when said shutter is in the closed position and said hood is taken out of said housing, a threaded portion upon the end of said drum facing the cover, and a spring-loaded screw passing through said cover and arranged to engage said portion and operative to draw said drum towards said cover.

10. In apparatus for the telegraphic transmission of pictures, a picture drum, a hood impervious to light adapted to envelope said drum, a light impervious housing adapted to house said hood and including a guiding cylinder, both said guiding cylinder and said hood having at the identical place a slot parallel to the common axis, a shutter shaped corresponding to the peripheral surface of said hood and adapted to control said slot, a cover for said hood rotatable with respect thereto, means for rigidly connecting said shutter 35 with said cover, said hood having an aperture on the side at which said shutter is located, a spring-controlled pin on said cover adapted to engage said aperture when said shutter is in the closed position and said 40 hood is taken out of said housing, a threaded portion upon the end of said drum facing the cover, and a spring-loaded screw passing through said cover and arranged to engage said portion and operative to draw said drum 45 towards said cover, and a projecting border at the other end of said drum adapted to form a light-proof seal with the adjacent edge of 50 the hood.

11. In apparatus for the telegraphic transmission of pictures, a picture drum, a hood impervious to light adapted to envelope said drum, a light impervious housing adapted to house said hood and including a guiding cylinder, both said guiding cylinder and said hood having at the identical place a slot parallel to the common axis, a shutter shaped corresponding to the peripheral surface of said hood and adapted to control said slot, a cover for said hood rotatable with respect thereto, means for rigidly connecting said

shutter with said cover, said hood having an aperture on the side at which said shutter is located, a spring-controlled pin on said cover adapted to engage said aperture when said shutter is in the closed position and said hood is taken out of said housing, a threaded portion upon the end of said drum facing the cover, and a spring-loaded screw passing through said cover and arranged to engage said portion and operative to draw said drum towards said cover, a projecting border at the other end of said drum adapted to form a light-proof seal with the adjacent edge of the hood, and a spring loaded lever mounted on said cover and adapted to engage an aperture in a part connected with the cylindrical part of said hood to prevent the turning movement necessary for the removal of said hood from said housing.

12. In apparatus for the telegraphic transmission of pictures, a picture drum, a hood impervious to light adapted to envelope said drum, a light impervious housing adapted to house said hood and including a guiding cylinder, both said guiding cylinder and said hood having at the identical place a slot parallel to the common axis, a shutter shaped corresponding to the peripheral surface of said hood and adapted to control said slot, a cover for said hood rotatable with respect thereto, means for rigidly connecting said shutter with said cover, said hood having an aperture on the side at which said shutter is located, a spring-controlled pin on said cover adapted to engage said aperture when said shutter is in the closed position and said hood is taken out of said housing, a threaded portion upon the end of said drum facing the cover, and a spring-loaded screw passing through said cover and arranged to engage said portion and operative to draw said drum towards said cover, a projecting border at the other end of said drum adapted to form a light-proof seal with the adjacent edge of the hood, and a spring loaded lever mounted on said cover and adapted to engage an aperture in a part connected with the cylindrical part of said hood to prevent rotation of said cover, said screw adapted to release said lever when operated to engage said drum, whereby rotation of said cover is prevented until said drum is connected to said cover.

In testimony whereof we affix our signatures.
